UNITED STATES PATENT OFFICE.

JAMES E. SINCLAIR, OF BALTIMORE, MARYLAND.

MACHINE FOR WASHING, SCOURING, AND BURRING WOOL.

SPECIFICATION forming part of Letters Patent No. 292,869, dated February 5, 1884.

Application filed March 2, 1883. (No model.)

To all whom it may concern:

Be it known that I, JAMES E. SINCLAIR, of Baltimore, in the State of Maryland, have invented a new and useful Improvement in Machines for Washing, Scouring, Burr 5 ing, and Picking Wool, of which the following is a full, clear, and exact description, reference being had to the annexed drawings, forming part of this specification.

10 This invention relates to machines for washing, scouring, burring, and picking wool by a continuous operation, and the invention consists of the novel construction hereinafter described and claimed.

15 In the drawings, Figure 1 is a longitudinal section of the machine. Fig. 2 is a plan view of the same. Figs. 3, 4, and 5 are parts of a longitudinal section of the machine enlarged; and Figs. 6, 7, 8, 9, 10, 11, 12, 13, and 14 are 20 detail views.

In treating wool preparatory to carding, I first pass it through a washing apparatus, A, in which the fibers are thoroughly separated and agitated in cold water to remove all foreign substances, such as grit and sand, and also lime, where the wool has been obtained 25 from pelts. From the washing apparatus the wool is pumped into a scouring apparatus, B, where it is treated with hot water and substances for removing the animal grease. As 30 the wool is thoroughly separated before it reaches the hot water, it need not be subjected to the heat long enough to injure the fiber, but may be quickly scoured, and pumped into the burring and picking apparatus C, where it is rinsed in cold water, and burred and picked, and finally discharged from the machine in 35 condition to be dried, and then carded.

The machine for carrying out the end I have 40 in view includes, then, the washing apparatus A, the scouring apparatus B, and the burring and picking apparatus C, as above indicated. The washing apparatus A comprises a tank or receptacle, D, having a hopper, E, leading thereto, and a drum, F, provided with teeth for feeding the wool from the hopper into the receptacle.

To facilitate the complete separation of the fibers of wool as they are drawn into the bath, 45 I provide a concave apron, G, at the front lower side of the drum, extending down from the hopper, which apron is formed of a series

of strips, g, provided with teeth g³, and supported on springs g⁴ and cross-bars g⁴ in such manner that they may be depressed to withdraw their teeth from the wool, to prevent the wool from accumulating thereon. I also provide a concave plate, g⁵, arranged inside the apron G, and having perforations g⁶, through which the teeth g³ project when the strips g⁴ are not depressed, and which plate is adapted to hold the wool while the teeth are being withdrawn therefrom.

Various means may be employed for giving a regular sinking and rising movement to the strips g by the rotation of the drum.

I have shown the drum provided with projections g², arranged on its periphery in spiral lines, (see Fig. 6,) and corresponding projections, f, on the strips g, against which the projections on the drum will strike and depress the strips. When the plate g⁵ is used, it is to be provided with slots g⁷, through which the projections f may extend, as shown in Figs. 7 and 8. The projections may be arranged in any desirable manner to give the necessary movement required for releasing any tufts of wool that may adhere to the teeth.

To prevent the wool from adhering to the teeth of the drum a brush, H, is arranged at the rear of the latter, which is to be rotated by suitable connections to clean the teeth and force the wool downward into the water. A pipe, I, entering the receptacle D at one side, will keep up a supply of water, which filters through the perforated cover h and the false bottom h' into the still-water chamber h², from which it is let off by means of the cock h³. The grit and sand will also drop through the false bottom h' and leave the main part of the receptacle D comparatively clean. At the opposite end of the receptacle D from the drum F are arranged two upright pumps, J, by which the wool is to be elevated to the traveling apron K outside of the said receptacle.

This apron is formed of suitable network to allow the water from the wool to drip through into the trough L, which has a false bottom, i, and an overflow-channel, i', by which the overflow water is conducted to the hopper E. With this construction a complete circulation of the water in the washing apparatus is provided for. From the traveling apron K the wool passes between the two

wringing-rollers M, and is brushed downward by the rotary brush N into the scouring apparatus B. The scouring apparatus comprises a conical hopper-shaped receptacle, O, and an upright conical drum, P, arranged therein. The inner surface of the receptacle O and the periphery of the drum are corrugated, so that as the drum is rotated and the wool drops down around the drum into the hot water which envelopes it, the wool will be subjected to a rubbing operation, which, together with the effect of the cleansing compounds used, will remove all animal grease therefrom. The hot water is supplied by a pipe, j, entering the receptacle Q at one side thereof, which receptacle is provided with a false bottom, j', leaving open communication below with the passage k, along which the wool is forced as it passes from the scouring-drum. The passage k has a perforated false bottom, k', leading to a still-water chamber, k², from which the dirt and water are drawn off through a cock, k³. The scouring apparatus is likewise provided with a pair of pumps, R, arranged in all respects like those in the washing apparatus for pumping the scoured wool to a traveling apron, S, similar to the apron K. The water dripping from the wool is run back into the scouring apparatus by means of the pipe m from trough l. From the traveling apron S the wool passes between the two wringing-rollers T, and is brushed downward by the rotary brush U into the burring and picking apparatus C. At the front of this apparatus is a toothed drum, D', fitted to revolve in a semicircular basin, E', and above the drum is arranged a rinsing device, F', consisting of a series of perforated cross-pipes adapted for spraying or jetting cold water over the said drum. As the water accumulates in the basin E' it discharges through an overflow-pipe, I, arranged on the outside of the machine and communicating with the receptacle of the washing apparatus already described. As the drum D' rotates, a brush, G', removes the wool from the teeth of the drum and brushes it into a receptacle, H', which has a drum, I', and a concave apron, J', similar to the drum and apron of the washing apparatus. Here the wool is again thoroughly separated, and as it is carried up by the drum it is met by the burring-drum K', which rotates in the opposite direction to that of drum I' and separates the burrs from the wool.

Underneath the drum K' is a false bottom, L', through which the burrs will fall, while the wool passes on to the picking-drum M'. To prevent the teeth of the burring-drum K' from acting on the wool longer than necessary, this drum is formed of two parts—an outer cylindrical shell, p', having perforations therein, and an inner drum, p², formed of bars q, having pins secured thereto, which are adapted to project through the perforations of the outer shell. The longitudinal axis of the inner drum, p², is located outside of the longi-

tudinal axis of the outer shell, p', (see Figs. 13 and 14,) and the ends of the bars q are adapted to move in a cam-groove, q', in the walls supporting the drum, so that the teeth of the drum will be drawn inward and within the outer shell as they pass to the rear, in the act of rotation. The teeth will thus cease to act on the wool when the latter reaches the upright grating N'. The slots in the grating N' are made narrow at the front side, as shown in Fig. 12, and flaring at the rear, to prevent the wool from wedging therein as it is drawn through the same by the picking-drum M'. The drum M' consists of two wheels, having bars r, secured thereto in a twisted or spiral form, as shown in Fig. 9, and provided with teeth which are slightly hooked at the ends. These teeth are adapted to extend partially through the grating, in order that they may reach the wool and draw it through. To the spokes of the two wheels of the drum are secured bars or blades s', which are to serve as fans for expelling the wool from the machine.

Owing to the great quantity of water that is required in washing and scouring wool, it is of the greatest importance that the water shall be utilized to the fullest extent.

It will be seen that I provide for the running of the water from the rinsing device to the washing apparatus, whereby it is made to do double duty, and by the arrangement of the troughs and pipes above described the water that is pumped up out of the washing and the scouring apparatus is returned to the same, respectively. A current is thus produced through both the washing and the scouring apparatus, which serves to carry the wool along until it is brought within the suction of the pumps.

The special construction of the scouring and the picking and burring apparatus will be made the subject of subsequent application for patent.

What I claim is—

1. A machine for treating wool, having a series of connected receptacles in which the wool is successively treated, and which receptacles are combined with one or more pumps for elevating the wool and water from one receptacle to another, and aprons and troughs for returning the elevated water to the receptacle from which it was drawn, whereby a circulation of the water in said receptacle will be produced to assist in carrying the wool through the machine, substantially as specified.

2. A machine for treating wool, having a series of receptacles in which the wool is successively treated, which receptacles are combined with pumps adapted to elevate the wool, traveling aprons, wringers, and brushes, the latter delivering the wool from the wringers, and pipes or troughs for returning the elevated water for repeated use, substantially as specified.

3. The machine herein described, consisting of the washing apparatus comprising a recep-

tacle and revolving toothed drum and elevating-pumps, the scouring apparatus connected to the washing apparatus by a traveling apron and wringers, and comprising a corrugated 5 conical drum and corresponding receptacle and elevating-pumps, and the burring and picking apparatus connected to the scouring apparatus by a traveling apron and wringers, and comprising a receptacle and a series of toothed 10 drums, all arranged and adapted to operate substantially as shown and described.

4. The apparatus consisting of the toothed drum, the wool and water receptacle, the concave apron formed of movable toothed bars, 15 and the rotary brush, all combined and adapt-

ed to operate substantially as shown and described.

5. The combination of a pump adapted for elevating the wool and water, with the wool and water receptacle, a trough for returning 20 the water, and a wringer for separating the water from the wool, substantially as shown and described, whereby a circulation of the water shall be obtained, for the purpose specified.

JAMES E. SINCLAIR.
